UNITED STATES PATENT OFFICE.

MICHAEL E. TOEPEL, FRANK B. WIDMAYER, AND ADOLPH POTDEVIN, OF NEW YORK, N. Y.

DESIGN FOR A CASING FOR HYDROCARBON-MOTORS.

SPECIFICATION forming part of Design No. 35,005, dated August 27, 1901.

Application filed March 18, 1901. Serial No. 51,790. Term of patent 7 years.

To all whom it may concern:

Be it known that we, MICHAEL E. TOEPEL, FRANK B. WIDMAYER, and ADOLPH POTDEVIN, citizens of the United States, and residents of New York city, in the county of New York and State of New York, have invented and produced a new and original Design for a Casing for Hydrocarbon-Motors, of which the following is a specification.

Our invention relates to the exterior appearance or design of a casing for hydrocarbon-motors.

Said design is illustrated in the accompanying drawings, wherein—

Figure 1 is a side elevation of the casing. Fig. 2 is a front elevation thereof; Fig. 3, a rear elevation thereof, and Fig. 4 a plan view thereof.

The leading or essential features of our design, as seen in the accompanying drawings, are the drum-shaped lower portion 5, surrounded by the cylindrical ribbed portion 6, topped by the ribbed cap 7, on the side of which is a vertically-ribbed projection 8, having depending therefrom along the side of the cylindrical portion 6 a conical portion 9, also provided with vertical ribs. The drum-shaped portion 5 has transverse ribs on its sides, as indicated at 10, and vertical ribs extending from one transverse rib to another, as indicated at 11. On the face of the drum-shaped portion 5 there is a radially-located elevated portion 12 in line with the depending portion 9. About the center of the head of the drum 5, as seen in Fig. 2, is a depression, (indicated at 20.) On the reverse side of the drum 5 and likewise on the obverse

side are peripheral projections 23, corresponding to the ribs 10 of Figs. 1 and 4, upon which projections appear hexagonal figures. At 40 the upper right-hand corner of the radially-raised portion 12 in Figs. 1 and 2 is a projection bearing a finger-like extension 25. Above this the ribs of the cylindrical portion 6 appear broken away, forming a channel. A 45 short cylindrical projection extends horizontally from the conical portion 9, as seen at 14 in Fig. 2. A longer cylindrical projection extends from the ribbed portion 8, as indicated at 15, and which is further prolonged by a 50 series of polygonal and cylindrical sections decreasing in size, as indicated at 16. Above the ribbed portion 8 is a plain cylindrical portion topped by a polygonal part 27. It will be noted that the ribs on the cylindrical 55 portion 6 decrease in diameter near the lower end of the series and that the thickness of drum 5 is less than the diameter of the smallest rib. It will also be noted that the radially-projecting ribs on the cap 7 are interrupted at four points, wherein appear polygonal bodies 28.

We claim as our invention—

The design of a casing for a hydrocarbon-motor as herein shown and described. 65

Signed at New York, in the county of New York and State of New York, this 16th day of March, A. D. 1901.

MICH. E. TOEPEL.
